ELECTRIC SWITCH

Frederic P. Gates, Toronto, Ontario, Canada, assignor to The Arrow-Hart & Hegeman Electric Company, Hartford, Conn., a corporation of Connecticut

Application March 26, 1937, Serial No. 133,254

20 Claims. (Cl. 200—15)

This invention relates to electric switches. More particularly it relates to electric switches particularly adapted for use in circuits including heater elements such as in electric ranges and 5 plates.

Heretofore electric switches for this type of service have most commonly been rotary snap switches or slow break lever operated switches in which the lever was capable of taking three or 10 more positions in a single plane of movement.

It is an object of this invention to provide an improved form of lever operated electric switch mechanism in which by swivelling the operating handle, the switch may be positioned for closing 15 the circuit to the heating elements of an electric range or the like to give three degrees of heat. Another object of my invention is to provide means preventing the swivelling of the switch mechanism while the switch is in circuit-closing 20 position. Another object of my invention is to provide a switch of the above type which is adapted for use in connection with either a two or three line power supply.

Another object of this invention is to provide 25 an electric snap switch particularly adapted for use in connection with electric ranges and the like in which switch the operation is controlled by a lever which operates a tumbler or over-center type of snapping mechanism.

30 Another object of this invention is to provide an electric switch for the above-mentioned type of service in which a tumbler or over-center type of mechanism is employed and which is capable of controlling the circuit connections to a two or 35 three element heating unit to give three or more degrees of heat from the unit.

Another object of my invention is to provide a 40 switch for the above type of service, which is mounted in a base similar to the bases heretofore used in connection with rotary snap switches, but in which the snap mechanism is of the tumbler or 45 over-center type.

Other objects and advantages will become apparent as it is described in connection with the 50 accompanying drawings.

In the drawings, Fig. 1 is a plan view of a switch embodying the principles of my invention. Fig. 2 is a vertical section view through a switch embodying the principles of my invention, with the 55 section being taken through the cover plate and upper parts of the switch on line 2—2 of Figure 1 but being taken through the insulating base and those parts of the switch which are housed within the base on line 2—2 of Figure 7. Fig. 3 is a vertical section view through the insulating

base of the switch shown in Figures 1 and 2 with the mechanism removed, the section being taken along line 3—3 of Figure 7. Figure 4 is a fragmentary vertical section view with the section being taken along line 4—4 of Figure 1. Figure 5 is a detail view showing in plan the bearing disc employed in this invention. Figure 6 is a detailed view showing in plan a supporting bridge or bearing plate employed in this invention. Figure 7 is a plan view looking into the interior of the invention with the cover and bearing plates removed and the bearing disc broken away partly for clearness. Figure 8 is a view similar to Figure 7 but with the switch in a different position. Figure 9 is a view similar to Figure 8 but with the 10 switch in a third position. Figure 10 is a detailed view showing in plan the indicator plate used in this invention. Figure 11 is a diagrammatic view of the switch as connected to a two-section resistor and a three-wire power supply line. This 15 view also indicates diagrammatically the degrees of heat produced when the switch is in its various angular positions. Figure 12 is a perspective view of the switch frame.

Figure 13 is a perspective view of an insulating 20 plate and auxiliary contact for mounting upon the bottom of the frame shown in Figure 12 in a modified form of switch.

Figure 14 is a vertical section view, taken along a plane similar to that indicated by 14—14 in Fig. 30 7, illustrating the invention in modified form, i. e., as is constructed when the plate of Fig. 13 is used.

Figure 15 is a transverse section view through the invention as modified according to Figures 13 35 and 14.

Figure 16 is a plan view partly in section taken along line 16—16 of Figure 17 showing a third form of invention.

Figure 17 is a vertical section view of the 40 invention shown in Figure 16 with the section being taken along line 17—17 of Figure 16.

Figure 18 is an elevation view partly in section of the switch mechanism used in the form of invention illustrated in Figures 16 and 17.

Figure 19 is an elevation view partly in section, of the switch mechanism used in the form of invention illustrated in Figures 16 to 18.

Referring to the drawings the switch is mounted behind a surface plate 10 and a sub-plate 10¹ such 50 as found in electric ranges. Against the top surface of the surface plate there lies a cast metal indicating member 12 having a pointed end 14 which indicates whether the switch is in position to complete the circuit for giving high, medium 55

and low degrees of heat. The indicator has a flat back face and on the front there is an arched central portion 16 with a longitudinal slot 18 therethrough. An operating lever 20 of the switch 5 tends through the slot 18 and has upon its outer end an insulating handle 22, the lower surface of which bears upon the curved surface 16 of the indicator and thus holds the indicator between the handle and the surface plate 10. A circular 10 aperture is provided in the plates 10 and 10^a and a pair of short arcuate lugs 24 (Figs. 2 and 10) project from the back surface of the indicator 12 into this aperture for the purpose of guiding the indicator as the switch operator is 15 moved into various angular positions, as herein-after described. Obviously the outside diameter of the lugs 24 will approximate the diameter of the aperture in plate 10.

The switch mechanism is mounted in an approximately circular insulating base 30 which is hollowed out centrally from its upper surface for the reception of the switch mechanism. The switch mechanism is mounted upon a U-shaped frame 32 (Fig. 11) of which the parallel identical 20 side arms have the irregular shape shown. The transverse or base portion of this frame has projecting down from it in a central position an axle 34 for swivelly mounting the frame. This axle passes through a spacing collar 36 which is 25 placed between the base of the frame 32 and a square metallic plate 38 which is mounted in a square recess in the floor of the insulating base. A lug 40 is turned up at right angles to the surface of the square plate 38 and has in registry with it, when the switch is in off position, a lug 42 which is bent down from the base of the switch frame. In order to hold these lugs in registry and thereby normally urge the switch frame into predetermined position, a spring 44 is coiled about the collar 36 and has its ends engaging with opposite 30 sides of the lugs 40 and 42.

A movable bridging contact member 46 is capable of actuation by conventional tumbler or over-center spring snapping mechanism by means of the operating lever 20 which is pivotally mounted 35 in the frame 32 by means of the pivot pin 48 extending transversely between the parallel frame arms. This type of switch mechanism is well known in the art and therefore it need not be described nor illustrated in detail. It will be sufficient to say that in a conventional fashion the bridging contacts 46 and 47 are mounted upon and insulated from a flat stamped sheet metal switching yoke 50 which swings to and fro between the switch frame arms in an arc of less than 90° under 40 the action of an over-center spring 52 which engages at one end with a transverse part of the switching yoke 50, and at the other, with the operating lever 20. Since the operating lever 20, switching yoke 50 and movable contact 46 are all 45 mounted upon the switch frame 32 it will be obvious that as the frame is swivelled about its axis 34 the whole switch mechanism will move as a unit with the frame.

Mounted upon an upper ledge in the switch base 50 are three fixed metallic contact members 60, 63 and 67 having contact fingers 61, 62, 64, 65, 66, 68 extending inwardly at various angles as may best be seen in Figures 7, 8, 9, and 11. At the opposite sides of the base and mounted upon a lower 55 level are three other fixed contact members 70, 73, 76, which have extending inwardly therefrom at various angles contact fingers 71, 72, 74, 75, 77 and 78. The angles at which the various contact fingers will extend is determined by the mov-

able contacts 46 and 47 which must engage with the various fixed contacts in the various angular positions of the switch frame and movable contacts.

By reason of the action of the coil spring 36, 5 the switch frame will always return to the normally central position which is shown in Figure 7 whenever the movable contacts are in open circuit position. In this central position the movable contacts may either be in open circuit position with the movable contact disengaged from all fixed contacts, or upon operation of the operating lever 20 the movable contacts may engage with certain of the fixed contacts, that is to say, movable contact 46 will engage with fixed contacts 62 (upper) and 72 (lower) while movable contact 47 will engage with fixed contacts 66 (upper) and 77 (lower). To this end the fixed contacts 62 and 72 will be in a single plane and fixed contacts 66 and 77 will be in another stationary plane parallel to the plane of contacts 62 and 66, the spacing of these planes being determined by the spacing of the movable contacts 46 and 47.

Now if, while the switch is in open circuit position, the handle 22 is grasped and the switch frame and mechanism is swivelled about the axis 34 into the angular position shown in Figure 8, then the operating lever 20 may be rocked about its pivot 48 to cause movable contacts 46 and 47 to snap into circuit-closing position. In this position movable contact 46 will engage with the fixed contacts 61 and 74 while movable contact 47 will engage with fixed contacts 65 and 78. The engagement of the stationary and movable contacts in this position will prevent the return of the switch frame to the central or normal position and the switch frame and mechanism may only return to central position when the operating lever is again moved to snap the movable contacts 46 and 47 to open-circuit position.

If, while the contacts are in open-circuit position, the switch frame is moved to the position shown in Figure 9 by grasping the handle 22 and swivelling the frame and mechanism about the pivot 34 then the movable contacts may be moved into a third closed-circuit position by rocking the operating lever 20 about its pivot 48. In this position the movable contact 46 will engage with fixed contacts 64 and 71 while the movable contact 47 will engage with fixed contacts 68 and 75. In this position again it is the engagement of these fixed and movable contacts which holds the switch frame and mechanism in this angular position against the tendency of the return spring 44 to return the switch frame and mechanism to the central position.

In order to hold the switch mechanism in the cavity of the insulating base a circular bearing disc 80 is secured across the upper ends of the switch frame 32 by means of lugs 82 extending from the upper ends of the arms of the switch frame 32 into complementary apertures 83 in the bearing disc 80 and having their ends peened over. Thus the bearing disc 80 will move as a unit with the switch frame. A diametrical slot 84 may be provided in the bearing disc for passage of the operating lever 20. Fitting loosely over this bearing disc 80 is a flanged bearing plate 86 whose diameter between flanges is approximately that of the bearing disc 80. Diametrical lugs 88 extend in opposite directions from the periphery of this flanged bearing plate 86 and seat upon the top edge of the switch base, being secured thereon by bolts 90.

- In order to resist movement of the switch frame from one angular position to another while the fixed and movable contacts are in engagement and consequently prevent damage to the fixed or movable contacts by the exertion of undue pressure in an attempt to change the angular position of the frame, a central aperture is provided in the bearing plate 86 having three radial finger-like extensions 86^a, 86^b and 86^c. When the switch 10 is in any one of the three circuit closing positions the operating lever will be located in one of the slots 86^a, 86^b and 86^c and the engagement of the sides of the lever with the sides of the finger-like extensions will prevent the rotation or swivelling of the switch frame about its axis. When the switch is in open-circuit position the operating lever 20 will be in the large segmentally shaped end 86^d of the aperture and therefore the lever is unhindered in its movement as attempt 20 is made to change the angular position of the switch mechanism.

If desired, the mounting plate 10 may be secured to the flanged bearing plate 86 by screws 89.

- If desired, the plates by which the fixed contacts of the switch are secured to the base may connect these contacts with wire terminal plates on the bottom face of the insulating base, for example, the contact plate 63 may be connected by bolt 90 to terminal plate 91 having a terminal screw 92.

- Referring to the diagram (Fig. 11) it will be noted that the switch may be connected to a resistor or heating unit having sections A and B by the following means: Wire 93 for connecting the contact plate 60 and to the outside of section B; wire 94 for connecting the mid-point of the sections A and B and to the contact plate 67; and wire 95 for connecting the outside of section A and the contact plate 63. The three-wire supply line may be connected as follows:

Outside wire, L¹, to contact plate 70
Neutral wire, N, to contact plate 73
Outside wire, L², to contact plate 76

- The various positions of the movable contacts 45 and 47 are illustrated in this diagram as follows:

In full lines the contact is in position to give a medium degree of heat in the heater unit. In 50 dot-and-dash lines the position of the switch for giving a high degree of heat is shown. The dotted lines show the switch in position to give a low degree of heat. Connections and circuits completed will be apparent to those skilled in the art upon inspection of the diagram in connection with the foregoing description.

- The form of invention just described is adapted particularly for use in connection with a three line power supply. If it be desired to use the 60 invention with a two line power supply this may be accomplished by affixing to the bottom surface of the switch frame 32 a sheet insulation plate 100 having thereon a narrow conducting strip 102, which functions as an auxiliary contact member and has ends 102^a and 102^c wrapped 65 around the edge of this insulating plate 100 in spaced positions directly opposite the contact members 67 and 73 when the switch frame is in mid or high heat position (see Figure 7). To engage with the end portions 102^a and 102^c there are provided additional stationary contact members 167 and 173 consisting of thin resilient strips of sheet metal whose outer ends are secured beneath the contact members 67 and 73. The contacts 75 75 and 173 are bent down into the base

cavity and their ends are reversely bent forming contact surfaces facing radially inward of the switch so as to rub against and make contact with the ends 102^a and 102^c of the movable contact 102 in the high heat position of the 5 switch. In the other positions of the switch these stationary contacts 167 and 173 are disengaged. In other details the switch, as described in connection with Figures 1 to 12, remains the same. 10

When the switch is to be used with a two-wire supply the contact members 70 and 76 will be connected to a single one of the power lines, the other power line being connected to the neutral contact member 73. The high, medium and low 15 heat positions of the switch will be exactly the same and the elements A, B, will be connected in parallel between the lines in high heat position and in series between the lines in low heat position and only element A will be connected 20 between the lines in the medium heat position.

My invention is equally applicable to a slow make and break type of switch. This form of the invention is shown in Figs. 16 to 19. There, the switch mechanism comprises a lever 220 pivoted 25 upon a pin 245 passing transversely through parallel vertical arms 232 which connect and space a plate 280 (similar to the plate 80 of the form of the switch previously described) and an insulating plate 201 (similar to the insulating plate 100). Mounted upon the lower end of the operating lever 220 is a peaked insulated cam 221 whose surfaces are adapted to move resilient movable circuit-making and breaking contacts 246^c and 247^c. These circuit-breaking contacts are mounted upon the insulating plate 201. The movable circuit-breaking contacts 246^c and 247^c are adapted, under the influence of operating lever 220, to engage and disengage fixed circuit-breaking contacts 248^c and 250^c which are also 30 mounted upon the upper surface of the insulating plate 201. It is the purpose and function of these circuit-making and breaking contacts to initiate and terminate the flow of current through the device and circuit. As will herein- 35 after appear, it is not possible to complete the circuit nor interrupt the flow of current through it by the engagement or disengagement of any other set of contacts in the device. 40

The circuit-breaking mechanism is swivelly 50 mounted so as to permit its movement into angularly spaced positions for high, medium or low heat connections to be made. The swivel mounting comprises a cylindrical cup 280 fixed centrally to the lower surface of the insulating 55 plate 201. Housed in the cup is a coil spring 281 which presses a ball 282 upwardly in position to engage the lower end of the operating lever 220 which is formed in the shape of a cam having indentations, such as 220^a, for the reception of the 60 ball as the lever is moved into extreme positions. This spring-pressed ball and the cam construction serve as indexing means to determine the positions of rest of the operating lever 220, i. e., the circuit-making and the open-circuit positions. An axial projection 284 extends from the bottom of the cylindrical cup 280 into a bearing plate 238 similar to the plate 38 in the previously described modification. The cup and switch mechanism may be oscillated about the projection 284 as an axis. 65

In order to return the switch mechanism to mid-position automatically a wire spring 244 is coiled around the outside of the cup 280 and engages with a lug 240 extending up from one edge 70 75

of the plate 238. Paralleling this lug 240 is an extension of the end of one of the arms 232. This extension passes through the insulating plate 201. The operation of this centering spring 5 244 is similar to the operation of the spring 44 in the modification previously described.

The switch mechanism may be held in the base by a flanged bearing plate, like plate 86 in Figs. 2, 4 and 6, and is held against swivelling while 10 in closed circuit position by engagement of lever 220 with one or another of slots 86, a, b, or c.

For the purpose of selecting the proper circuit and establishing its connections to give the high, medium and low degrees of heat, six stationary contact members 260, 263, 267, 270, 273, 15 276 are positioned around the base. These members may be considered as selector contacts for they are adapted to be connected selectively with movable selector contacts 246^a, 247^a, 248^a, 250^a (hereinafter more particularly described) as the 20 circuit breaking mechanism, is swivelled about axis 284. Each of the stationary selector contacts, for example 273, has a terminal portion seated in a recess in the upper face of the switch base 200 and a mid-portion running down into the base cavity along the inside base wall and connecting with a contact portion 273^c projecting radially inward in a transverse plane midway down in the cavity of the switch base.

30 For engagement with stationary selector contacts 260^c, 263^c, 267^c as the mechanism is swivelled, there are attached to, or formed integrally with, the movable circuit breaker contacts 246, 247, the two movable selector contacts 246^a, 247^a. These contacts 246^a, 247^a may lie upon the upper 35 surface of the insulating plate 201. Similar movable selector switch contacts 248^a, 250^a lie on the upper surface of the insulating plate 201 and are attached to, or formed integrally with, stationary circuit breaker contacts 248, 250. Contacts 248^a, 250^a are for selective engagement with stationary selector contacts 270^c, 273^c, 276^c.

Referring now to the selector contacts and the circuit connections established when the switch mechanism is in the various angular positions, it will be noted that the contact portions 260^c, 263^c, 250^c of contacts 260, 263, 250 are elongated in a clockwise direction and that contact portion 276^c of contact 270 is elongated in a counter-clockwise direction so that each of these will be engaged by one or another of the movable selector contacts in two succeeding switch positions. The connector contacts 267^c and 273^c are of normal size and will not be engaged by the same movable connector contact in two succeeding positions.

In the high heat position (Fig. 16) movable selector contacts 246^a, 247^a engage stationary contacts 260^c, 263^c respectively and likewise 248^a, 60 250^a engage 270^c and 276^c respectively. The current from the outside lines of the three power line supply goes through resistor elements B and A in series, and the neutral will be connected to the midpoint between the elements A and B, 65 provided the switch is constructed with an auxiliary connector and contacts similar in function to the connector 102 of the previously described form of invention.

Such an auxiliary connector 290 is shown as 70 mounted on the bottom face of the insulating plate 201 by which it is insulated from the other conducting parts carried by said plate. It may be arcuate with two end portions extending toward but not over the edge of the insulating plate 75 201. These two end portions will engage

with two extra stationary selector contacts (see for example 373). These extra contacts may be similar in shape to the connector contacts 273 and 267 and may lie beneath the contacts 273 and 267. As in the case of the previously described form of invention this auxiliary connector makes it possible to use the invention with either a two or a three wire supply line.

When the switch is in open circuit position the circuit breaking mechanism may be swivelled 10 clockwise and operated to close the circuit for low heat connections. In this position movable connector contact 246^a will engage stationary connector contact 263^c, and similarly 247^a will engage 267^c; while 250^c will engage 273^c and 248^c 15 will remain in engagement with 270^c.

When the switch is in open circuit position the circuit breaking mechanism may be swivelled counter-clockwise from midposition and operated by lever 220 to close the circuit for medium 20 heat connections. In this position, movable connector contacts 246^a, 247^a and 248^c will remain in contact with fixed connector contacts 260^c, 263^c and 270^c respectively, with which they engaged in high heat position, and movable connector contact 250^c will be in engagement with 25 fixed connector contact 273^c.

Only in the high heat position will the auxiliary connector engage with its fixed contacts.

It will be observed that in each of the forms of the invention the circuit making and breaking mechanism, whether of the "snap" type or not, may be swivelled into several positions, wherein the movable circuit breaking contacts may be operated to close the circuits for high, low and medium heat, and that while the circuit is completed the mechanism can not be swivelled. Thus, the circuit can not be opened at the connector contacts, nor can the switch contacts be damaged by inopportune attempted swivelling 40 of the mechanism.

Many modifications within the scope of this invention will occur to those skilled in the art and therefore I do not limit my invention to the specific embodiments of the switch as described 45 and shown. By re-arrangement, omission or substitution of various of the fixed contacts the switch may be adapted for use in other circuits than that described and illustrated.

I claim:

1. In a snap switch, an operating member, a pivotally mounted movable contact, snapping mechanism for moving said movable contact into closed-circuit and open-circuit positions with a snap motion upon movement of said member, 55 supporting means for said member and contact and mechanism movable into angularly spaced positions, and fixed contacts angularly spaced for engagement by said movable contact in different angular positions of said supporting means.

2. In a snap switch, an operating member, a movable contact, snapping mechanism including an over-center spring for actuating said movable contact between open-circuit and closed-circuit positions upon movement of said operating member, supporting means for said member and contact and mechanism movable into angularly spaced positions, and fixed contacts angularly spaced for engagement by said movable contact in different angular positions of said supporting means.

3. In a snap switch, an operating member, a movable contact, snapping mechanism for actuating said movable contact between open-circuit 75

- and closed-circuit positions upon movement of said operating member, supporting mechanism for said member and contact and mechanism movable into angularly spaced positions, fixed contacts angularly spaced for engagement by said movable contact in different angular positions of said supporting means, and means to automatically return said supporting means to a predetermined one of said angular positions 10 when said fixed and movable contacts are disengaged.
4. In a snap switch, a reciprocating operating lever, a pivotally mounted movable contact, snapping mechanism including an over-center spring for actuating said movable contact between open-circuit and closed-circuit positions upon movement of said operating lever, swivelly mounted supporting means for said lever and contact and mechanism movable into angularly spaced positions, and fixed contacts angularly spaced for engagement by said movable contact in different angular positions of said supporting means, and means to automatically return said supporting means to a predetermined one of said angular positions when said fixed and movable contacts are disengaged.
5. In a snap switch, an operating member, a movable contact, snapping mechanism for actuating said movable contact with a snap motion upon movement of said member, supporting means for said member and contact and mechanism movable into angularly spaced positions, and fixed contacts angularly spaced for engagement by said movable contact in different angular positions of said supporting means, and means other than the engagement of the fixed and movable contacts for holding said supporting means angularly immovable while said fixed and movable contacts are engaged but being freed for movement upon disengagement of said fixed and movable contacts.
6. In a snap switch, a reciprocating operating lever, a pivotally mounted movable contact, snapping mechanism including an over-center spring for actuating said movable contact between open-circuit and closed-circuit positions upon movement of said operating lever, swivelly mounted supporting means for said lever and contact and mechanism movable into angularly spaced position, said movable contact moving in a plane parallel to said swivel axis, fixed contacts angularly spaced for engagement by said movable contact in different angular positions of said supporting means, said fixed contacts having their contact faces extending in angularly spaced planes parallel to said swivel axis.
7. In a snap switch, a reciprocating operating lever, a movable contact, snapping mechanism for actuating said movable contact with a snap motion upon movement of said lever, swivelly mounted supporting means for said lever and contact and mechanism, said movable contact moving in a plane parallel to said swivel axis and fixed contacts angularly spaced for engagement by said movable contact in different angular positions of said supporting means, said fixed contacts having their contact faces extending in angularly spaced planes parallel to said swivel axis, and means to automatically return said supporting means to a predetermined one of said angular positions when said fixed and movable contacts are disengaged, said automatic means being held inactive when said fixed and movable contacts are engaged.
- 75 8. In a snap switch, an insulating base, a mov-
- able contact movable in planes perpendicular to the bottom of the base, an operating lever, snapping mechanism for moving said contact into open-circuit and closed-circuit positions, a frame supporting said lever and contact and mechanism and movable into angularly spaced positions, means for swivelly mounting said frame in said base, and fixed contacts angularly spaced around said base for engagement by said movable contact in different angular positions of 10 said supporting frame.
9. In a snap switch, an insulating base, fixed contacts mounted on said base in angularly spaced relation, a movable contact, snapping mechanism for moving said movable contact into open and closed-circuit positions with a snap movement, an operating lever for said snap mechanism, a frame upon which said mechanism and movable contact and lever are mounted, means for swivelly mounting said frame whereby 15 said movable contact may engage with different sets of said fixed contacts when said frame is moved into different angularly spaced positions, said swivel mounting including a bearing disc movable with said frame, a bearing plate mounted on said base and guiding the rotation of said disc, said plate having recesses therein whose margins are engaged by said operating lever in its various circuit-closing positions to prevent 20 swivelling of said frame while the fixed and movable contacts are in engagement.
10. In an electric switch, a base, a plurality of fixed contacts mounted thereon, switching mechanism for completing and interrupting the circuit between certain predetermined and selected fixed contacts, a pivotal mounting for said mechanism enabling it to be swivelled into a plurality of different angular positions, means apart from said contacts for preventing swivelling of said mechanism while the circuit is closed, 25 and means terminating the swivel movement of said switching mechanism when said contacts are in register whereupon said switch mechanism may be operated to cause circuit completion.
11. In an electric switch, a base, a plurality of fixed contacts mounted thereon, switching mechanism including relatively movable contacts for completing and interrupting a circuit, a pivotal mounting for said mechanism enabling it to be swivelled into a plurality of different 30 angular positions, circuit selecting contacts engaged and disengaged by said swivel movement and means to prevent swivelling of said mechanism, while the circuit is completed.
12. In an electric switch, a base, a plurality of fixed contacts mounted thereon, switching mechanism including a manual operator and a movable contact for completing and interrupting the circuit between certain predetermined and selected fixed contacts, a pivotal mounting for 35 said mechanism enabling it to be swivelled into a plurality of different angular positions, means other than a contact affixed to said base and engaged by said manual operator in closed circuit positions to prevent swivelling of said mechanism, and means terminating the swivel movement of said switching mechanism when said contacts are in register whereupon said switch mechanism may be operated to cause circuit completion.
13. In an electric switch for selecting a predetermined circuit arrangement and making and breaking the circuit thereto comprising a plurality of fixed contacts adapted for different circuit connections, circuit making and breaking 40
